VALVE LIFTER

Gies W. Hiley, Smithboro, N. Y.; Goldie E. Hiley
administratrix of said Gies W. Hiley, deceased

Application April 5, 1940, Serial No. 328,102

4 Claims. (Cl. 74—518)

This invention pertains to ratchet lever power mechanisms and is particularly applicable for operating a plunger or other sliding or reciprocating part on any kind of machine or for use as a valve lifter for compressing the spring on the valve stem of an internal combustion engine or for other analogous purposes. Such spring compressors facilitate disconnecting the valve for its removal from a motor.

One purpose of this invention is to provide a ratchet lever mechanism that is actuated by a lever in such a way as to elevate the entire lever as the lever handle is pushed down toward a valve or other element to be lifted. A further object is to mount a ratchet lever in such a way that as the lever is elevated as a whole, its effective leverage is increased by simultaneous alteration of relationship between its relative fulcrum points.

These and other objects will become apparent in the following illustrative description of this invention. A particular embodiment of this invention is described in the accompanying drawing, while the scope of the invention is more fully pointed out in the appended claims.

In the drawing:

Figure 1 represents an assembly view of the power mechanism as used as a valve lifter, showing the same in side elevation with a portion of the lifter in vertical section;

Figure 2 represents an enlarged side view of the lever arrangement of Figure 1;

Figure 3 represents a top plan view of the ratchet lever of Figure 2; and

Figure 4 represents a horizontal cross section of a portion of the mechanism along the line 4—4 of Figure 2, showing the relationship of a portion of a movable frame with respect to a standard for the lever support.

Referring more particularly to the drawing, a rigid pedestal 1 is shown with its upper portion encompassed by a relatively movable frame 2. A generally U-shaped arm 3 extends from the frame to terminate in a fork 4 under the pedestal so as to engage and lift the spring of a valve upon which the pedestal is to rest. On the upper portion of the movable frame 2 are opposing arms 5 and 6.

A lever 7 is mounted in the upper part of the movable frame 2 to fulcrum against the pedestal 1 and to slide in the arms 5 and 6. This sliding of the lever is controlled by the disposition of certain pins that connect the lever to these arms 5 and 6. To this purpose, the work end of the lever is provided with a pin or roller 8; and the

frame arm 5 is provided with a slot 9 to receive the pin 8. In the opposite arm 6 is a slot 10 to receive a pin 11 from an intermediate portion of the lever 7. This arm 6 is disposed angularly so as to diverge downwardly from the frame. From Figure 3 it is evident that the arm 5 is bifurcated so that the roller 8 slides with its ends in the respective slots 9 of the pair of arms 5. Similarly, the opposing diverging arm 6 is bifurcated so that the lever cross pin 11 is guided by its ends in the pair of slots 10.

Between these pins 8 and 11, the lever 7 is fulcrumed upon a roller 12 which is mounted upon the rigid pedestal 1. The portion 13 of the lever that bears upon the fulcrum roller 12 is arcuate as illustrated in Figures 1 and 2. Thus as the handle of lever 7 is forced downwardly, the lever is drawn toward the handle because of the guiding action upon the pin 11 of the angularly disposed slot 10. Thus the arcuate portion of the lever constituting the fulcrum and also the end roller 8 are drawn toward the handle of the lever. However, this motion is accompanied by elevation of the end roller 8 and so of the arm 5. Consequently, the entire movable frame is elevated, including the portions 2, 6, 3 and 4.

To secure the lever at any intermediate position a pawl 21 is pivoted to the lever 7 while a ratchet face 22 is formed along the upper edge 30 of the divergent arm 6. The pawl 21 is held normally in the teeth of this ratchet by a clip spring 23 inserted between the pawl and the lever arm 7. To release the pawl a simple finger grip lever 24 mounted upon the handle of the lever is connected to the pawl by a link 25.

The fixed pedestal portion 1 of this apparatus comprises a central post enlarged at its top 14 to a sliding fit within the column 2 of the movable frame. This enlargement of the pedestal 1 is sufficient in length to stabilize or maintain alignment of the frame 2. Moreover, a shoulder 15 is formed within the cylinder of frame 2 to surround the pedestal 1 and likewise to maintain longitudinal alignment of the frame 2. Between the pedestal head 14 and the frame shoulder 15 is interposed a compression spring 16. Thus as the frame 2 is elevated the shoulder 15 compresses the spring 16 against the bottom of a pedestal head 14. This tends to keep the two elements, pedestal 1 and movable frame 2, relatively movable.

The lower portion of the pedestal 1 is threaded. Upon this is threaded a base 17 adapted to rest upon an engine valve, for example, and adapted by reason of the threading to adjust the appara-

tus upon its base or, in other words, to adjust the space between the pedestal 1 and the roller foot or claw portion 4.

A coarser adjustment may be effected by arranging slots 18 in the outer surface of the frame 2 and providing a split throat 19 to encircle the movable frame 2. Through this split throat is a cross bolt 20 to slide into one or another of these slots 18. This split throat serves to secure the work arm or U-arm 3 to the frame 2. As shown, the arm 3 is swiveled between the split throat 19 and the roller claw 4. Thus a coarse adjustment of the arm 3 and claw 4 may be provided along the frame 2 while a fine adjustment is effected by the threaded base 17 of the pedestal 1.

In operation, one may press down upon the lever 7 and thus elevate the frame 2 and its associated parts. At the same time, the entire lever 7 is elevated correspondingly. Moreover, as the handle of the lever is depressed, the lever is drawn toward the operator. Consequently, the effective lever arm of the resistance of roller 12 is diminished and therefore the leverage or ratio of lever arms between the applied force to the resisting force is increased. Thus the actual force to depress the lever remains substantially constant while practical ease of depressing the lever is maintained because the entire lever is raised as the valve lifter is raised. Moreover, the effect of friction at the fulcrum point is minimized inasmuch as the roller 12 cooperates with the arcuate bearing portion 13 of the lever as to minimize friction. On the other hand, when the lever is released as the pawl is withdrawn from its engaging ratchet teeth, the handle of the lever moves slowly as the lever nears its upper position.

This invention has been described with reference to an illustrative embodiment as applied to valve lifter. However, it is contemplated that other applications of this invention will occur in which are utilized the novel features pointed out in the appended claims.

While in accordance with the patent statutes, I have described the principles of this invention and illustrated a preferred embodiment thereof, it will now be apparent to those skilled in the art that modifications and alterations may be made within the scope of the appended claims.

What I claim is:

1. A power transmission mechanism comprising a rod member, an anti-friction bearing element at the upper end of the rod member, a tubular frame member mounted for upward and downward sliding movements on the rod member, a spring in said frame member normally acting to force the rod member upwardly in the frame member, arms projecting from opposite sides of the frame member, a lever, guiding means mounting the lever at one end to swing vertically and to slide horizontally on one of the arms, and guiding means mounting the lever at an intermediate point in its length to slide on the other arm in a plane inclined downwardly and outwardly from a level above the level of the first-named arm, said lever being free from connection with the rod member and having an arcuately curved surface contacting with said anti-friction bearing element and mounting it to swing vertically and shift longitudinally on the rod member at a point between its connections with said arms.

2. A power transmission mechanism compris-

ing a rod member, an anti-friction bearing element at the upper end of the rod member, a tubular frame member mounted for upward and downward sliding movements on the rod member, arms projecting from opposite sides of the frame member, a spring in said frame member normally acting to force the rod member upwardly in the frame member, a lever, guiding means mounting the lever at one end to swing vertically and to slide horizontally on one of the arms, guiding means mounting the lever at an intermediate point in its length to slide on the other arm in a plane inclined downwardly and outwardly from a level above the level of the first-named arm, said lever being free from connection with the rod member and having an arcuately curved surface contacting with said anti-friction bearing element and mounting it to swing vertically and shift longitudinally on the rod member at a point between its connections with said arms, and locking means for locking the lever to the second-named arm at any point in the length of its guiding connection therewith to hold the rod and frame members in relatively shifted positions against the pressure of the spring.

3. A power transmission mechanism comprising a rod member, an anti-friction bearing element at the upper end of the rod member, a tubular frame member mounted for upward and downward sliding movements on the rod member, a spring in said frame member normally acting to force the rod member upwardly in the frame member, arms projecting from opposite sides of the frame member, a lever, guiding means mounting the lever at one end to swing vertically and to slide horizontally on one of the arms, a guide member on the frame connected with the other arm and having a guide slot and guiding means on the lever engaging said slot and mounting the lever at an intermediate point in its length to slide in a plane inclined downwardly and outwardly from a level above the level of the first-named arm, said lever being free from connection with the rod member and having an arcuately curved surface contacting with said anti-friction bearing element and mounting it to swing vertically and shift longitudinally on the rod member at a point between its connections with said arms, and pawl and ratchet locking means for locking the lever to the guide member against the pressure of the spring on the rod at any point in the length of its guiding connection therewith.

4. A power transmission mechanism comprising a rod member, a tubular frame member mounted for upward and downward sliding movements on the rod member, arms projecting from opposite sides of the frame member, a lever, guiding means mounting the lever at one end to swing vertically and to slide horizontally on one of the arms, guiding means mounting the lever at an intermediate point in its length to slide on the other arm in a plane inclined downwardly and outwardly from a level above the level of the first-named arm, said lever being mounted to swing vertically and shift longitudinally on the rod member at a point between its connections with said arms, a rack extending along the second-named arm in a path parallel with the path of the said outwardly and downwardly inclined guiding means, and a pawl on the lever for locking engagement with said rack.

GIES W. HILEY.
